METHOD OF AND MEANS FOR PRODUCING
ANTIRAVEL FABRICS

George W. Goetsch, Elkins Park, and Otto F. Smetana, Philadelphia, Pa., assignors to Quaker Hosiery Company, Philadelphia, Pa., a corporation of Pennsylvania

Application November 12, 1932, Serial No. 642,346

9 Claims. (Cl. 66—198)

This invention is concerned with the production of anti-ravel fabric, intended more particularly for stockings and the like, that is to say, to knitted fabrics which are secure against running consequent upon loop rupture. More specifically, this invention has to do with the production of anti-ravel fabric wherein alternate loops of certain courses interlock with contiguous wale loops of adjacent intermediate plain courses.

Considered from the broadest standpoint, our invention is directed toward making it possible to expeditiously and economically produce anti-ravel fabric characterized as above, through provision of a novel method capable of being practiced on flat knitting machines of the "cotton" type such as are ordinarily used in the manufacture of full fashioned stockings, equipped with lace attachments.

The method of producing non-ravel fabric in accordance with our invention, involves, as one of its steps, the pre-forming of loop courses without casting; and as another of its steps, the drawing of the loops of a previously completed course over the aforesaid pre-formed loops while the latter are held in the hooks of the needles of the knitting machine, and the lateral transfer of alternate loops of such previously completed loops to adjacent needles. The first of these two steps we are enabled to accomplish, through provisions whereby, while the machine performs a knitting cycle, the cam shaft is shifted through but a fraction of the usual distance necessary to initiate a narrowing cycle, so that the needle bar may be actuated during part of a revolution by a low rise (radially considered) of the auxiliary section of the knitting cam which is ordinarily used during narrowing, instead of by the higher rise of the knitting cam itself, to the end that the needles are depressed only sufficiently to measure the loops for the pre-formed course over the nibs of the sinkers without drawing of such loops through the loops of the previously completed course held on the shanks of the needles.

Another consideration essential to the successful production of anti-ravel fabric by our novel method is that during the lateral transfer of alternate loops in the second of the aforementioned steps, it is requisite that the beards of intermediate needles (those from which no loops are taken) be pressed for release and casting of the loops of the previously completed course over the corresponding loops of the pre-formed course. This operation we predetermine by use in the lace bar of the machine of special short points in alternation with the regular transfer

points of the usual length, capable of closing the beards of alternate needles without penetrating the loops on them.

Other objects and attendant advantages of this invention will be manifest from the detailed description following in connection with the attached drawings, wherein Fig. I is a diagrammatic view showing a fragment of knitted fabric such as may be produced by our novel method and means.

Figs. II, III, IV, V, VI, VII, VIII and IX are detail views showing successive steps in the production of the fabric of Fig. I in accordance with our new method.

Fig. X is a cross sectional view of a full fashioned stocking knitting machine suitably modified for the purposes of our invention.

Fig. XI is a fragmentary view of the machine looking as indicated by the arrows XI—XI in Fig. X.

Fig. XII is a fragmentary perspective view of the cam shaft of the machine showing the cam for actuating the needle bar; and

Fig. XIII is a fragmentary perspective view of the lace bar of the machine with the special and regular points to which reference has been previously made.

Referring first to Fig. I of these illustrations, the fabric there delineated, is characterized by courses 15 whereof alternate loops 15a are doubled with alternate contiguous wale loops 16b of adjacent plain courses 16, this being effected by lateral transferring of the loops 15a as hereinafter set forth in detail. In the present instance, there is a plain course 17 intervening each pair of the interlocking courses 15 and 16. If desired, however, the number of such intermediate plain courses 17 may be increased. For convenience of exemplification we have shown the loops 15a of one course 15 as being transferred to the left, and the loops 15a of the next course 15 to the right, and so on. Again, if desired, such transferring may be effected always in one direction throughout the fabric, i. e. either always to the left, or always to the right. Stippling has been resorted to in Fig. I merely to distinguish the courses 16 of the fabric from the others, thereby to facilitate the understanding of certain steps in our novel method of knitting whereof the description immediately follows.

In Figs. II—VII we have indicated the needles, the sinkers and the knock overs of the full fashioned stocking knitting machine shown in Figs. X and XI respectively by the letters N, S and

K, these instrumentalities all cooperating in the usual well known manner to form fabric loops. In Figs. VIII and IX alternate needles have been identified by the character N' for the purpose of distinction in further explanation. The lace bar of the machine shown in part at B in Fig. XIII, differs from the usual type of lace bar in that it has special alternate points P which are shorter than the regular intermediate points indicated at P, for capacity to function merely as needle beard pressers in the manner presently manifested.

Tracing the successive steps of our new method of knitting, the needles N are shown in Fig. II as occupying their raised position in readiness to take fresh yarn Y which has just been laid over the nibs of the sinkers S. Concurrently with descent of the needles N, N' so that their hook tops come slightly below the nibs of the sinkers S, the yarn Y is formed into loops 16a, 16b, as shown in Fig. III, for a course 16; but the beards of the needles are not closed at this time so that the previously drawn loops held on the shanks of the needles are not cast. Incident to the succeeding elevation of the needles N, N', the newly formed loops 16a pinched or wedged within the narrow upper ends of the needle hooks under the spring action of the beards are carried up with the needles as shown in Fig. IV, as a consequence of wedging of the yarn in the needle hooks while the previously formed loops 15a are held depressed by the sinkers S. The points P and P' are thereupon brought into contact with the needles N, N' to cover the beards of the latter as in a lace forming narrowing cycle as shown in Fig. V, and caused to descend with said needles as in Figs. VI and VIII. From Fig. VIII it will be observed that only the points P' penetrate the previously formed loops on the needles N, N' as ordinarily. The needles N, N' and the points P, P' rise together for a time (likewise as in a narrowing cycle) and eventually separate as in Figs. VII and IX. Incidentally the loops 15a are lifted by the points P' from the needles N over the pre-formed loops 16a of the course 16, and while the lace bar B continues to rise, the intermediate loops 15b of the course 15 are released by the special short points P, the regular points P' however still retaining the loops 15a as shown in Fig. IX. The lace bar B is next shifted laterally to the extent of one needle, and thereupon caused to descend once more so that the loops 15a on the points P' are deposited onto the needles N'. After deposit of the loops as just explained, the needles N, N' and points P, P' rise together, the points to their normal position of inactivity and the needles to the feeding position shown in Fig. II. Fresh yarn is again served and formed into fabric loops of a plain course 17 incident to a final reciprocation of the needles N, N', the needle beards being all pressed in the usual way, this time to cast the loops 15a, 16b and 16a respectively. The described cycle is continuously repeated with incident transfer of the loops to the right in one cycle and to the left in the next for corresponding disposal of said loops in opposite directions in alternate of the courses 16 of the fabric as previously explained in connection with Fig. I. The full fashioned stocking knitting machine illustrated in Figs. XI and XII is, generally speaking, standard in construction in that it comprises a cam shaft 20 which is supported for rotation and endwise shifting in spaced transverse frames whereof one is indicated at 21 in

Fig. X. Up and down movements are imparted to the needle bar 22 of the machine through a lever 23 which is affixed, together with an arm 24, to a longitudinal rock shaft 25, said arm having a roller 26 that runs in peripheral contact with the rotary knitting cam 27 on the cam shaft 20. The dipping frame 28 of the narrowing mechanism of the machine is actuated by another rotary cam 29 on the cam shaft 20, the intermediate connections including an arm 30 fulcrumed at 31 and carrying a roller 32 to cooperate with the cam 29, and a vertical link bar 33 connecting said arm with the dipping frame. Normally, the roller 32 rides a concentric disk 35 alongside the cam 29. The cam 27 for actuating the needle bar 22 is of the usual design as regards the general contour of its two sections 27a, 27b which are employed respectively during knitting and narrowing; but for the purposes of our invention, the width of the rise 47 of the section 27a has been reduced somewhat, by cutting away of its inside face, and its periphery made to merge smoothly with that of the section 27b at the region x-x (Fig. XII), the usual region of mergence between the two cam sections being at y-y. Normally, to initiate a narrowing cycle, the cam shaft 20 is shifted toward the right by the shifting mechanism comprehensively indicated at 36 under control of the usual measuring chain 37 which is provided with extra buttons 38 for lace knitting. In order to enable partial shifting of the cam shaft 20, likewise for the purposes of our invention, we provide the machine with a supplemental shifting mechanism 39 which is controlled by a separate chain 40 having buttons 41 corresponding in number and position to those of the measuring chain 37. The chain 40 is progressed in unison with the measuring chain 37 through suitable connections, not shown. The supplemental shifting mechanism 39 is an exact duplicate of the mechanism 36 except in that the side cam ridge 42 of the right hand disk 43 on the shaft 20 which cooperates with the shifting roller 44 is of less width by a half than the side cam ridge 45 of the corresponding disk 46 of the mechanism 36. As shown in Fig. XI, the disks 43 and 46 of the mechanisms 39 and 36 are set on the cam shaft 20 with the high portions of their cam ridges 42 and 45 angularly spaced to determine successive shifting of said shaft.

The formation of a course 16 of the fabric of Fig. I begins with a knitting cycle of the machine; but before the shaft 20 completes the revolution for such cycle, it is shifted part way (made possible by cutting away of the cam 27 as above explained) under the control of the supplemental shifting mechanism 39 when the mergent line x-x (Fig. XII) of the cam 27 is opposite the roller 26 on the arm 24, so that said roller instead of riding on the high rise 47 (considered radially) of the section 27a of said cam, rides the lower rise 48 of the auxiliary section 27 of the cam which is used during narrowing, while the roller 32 still remains on the concentric disk 35 associated with the cam 29—all as shown in Figs. X and XI. Accordingly the needles N, N' are lowered only to the extent illustrated in Fig. III to measure the loops 16a of the yarn Y over the sinkers S. Immediately upon completion of the same rotation of the shaft 20 with the mergent portion y-y of the cam 27 opposite the roller 26, said shaft is shifted under control of the measuring chain 38 all the way to the right for the performance, during the next revolution of

the shaft, of a usual narrowing cycle incident to which the roller 26 rides the section 27b of the cam 27 and the roller 32 rides the cam 29, to effect the transfer loop operation of Figs. 5 V-IX.

The mechanism for shifting the lace bar B incident to transfer of fabric loops between the needles N, N' may be of the well known type, and for this reason, a showing thereof has been omitted from the drawings.

Having thus described our invention, we claim:

1. The method of producing anti-ravel fabric on a full fashioned knitting machine having a lace attachment including a lace bar with alternate regular, and intermediate special short points, which comprises pre-forming a course of new loops over the nibs of the sinkers of the machine without casting the old loops of a previous course from the needles; then drawing old loops from alternate needles by aid of the regular points of the lace bar over the corresponding pre-formed loops of the new course, with incidental casting of old loops from the intermediate needles due to closure of the beards of the latter by the short special points of the lace bar; then transferring the loops on the regular points of the lace bar to other needles; then knitting a plain course on the needles; and continuously repeating the described cycle. 20

2. The method of producing anti-ravel fabric on a flat knitting machine having a lace attachment including a bar with alternate long and special short points, which comprises preforming a course of new loops over the nibs of the sinkers of the machine without casting the old loops of a previous course from the needles; then drawing old loops from alternate needles over the corresponding pre-formed loops of the new course by aid of the points of the lace bar, with incidental casting of the old loops from the intermediate needles due to closure of the beards of the latter by the short points of the lace bar; then transferring the alternate old loops on the long points of the lace bar to contiguous needles; then knitting a plain course; and continuously repeating the described cycle. 40

3. In a full fashioned knitting machine, a bar with needles; cooperative sinkers; a cam shaft; a rotary cam on said cam shaft with adjoining sections respectively for actuating the needle bar during knitting cycles and for actuating the needle bar during narrowing cycles; and means for shifting the cam shaft to enable the use of a portion of the narrowing section of the cam during a part of a rotation of said shaft for the purpose of pre-forming a new course of loops over the nibs of the sinkers without incidental casting of the loops of a previous course on said needles. 50

4. In a full fashioned hosiery knitting machine, a bar with needles; cooperative sinkers; a cam shaft with a cam thereon having a section for actuating the needle bar during knitting cycles, and an auxiliary section for actuating the needle bar during narrowing cycles; lace mechanism including a dipping frame and a lace bar with points to transfer fabric loops between adjacent needles; a normally idle cam on the cam shaft for actuating said dipping frame; means for shifting the cam shaft to permit operation of the last mentioned cam to determine performance of the machine of narrowing cycles for lace purposes; 60

and supplemental means for partially shifting the cam shaft to enable, during a part rotation of said shaft, use of a portion of the auxiliary section of the knitting cam aforesaid to actuate the needle bar for the purpose of pre-forming a course of new loops over the nibs of the sinkers without incidental casting of the loops of the previous course on said needles, and without initiating a narrowing cycle. 80

5. In a full fashioned hosiery knitting machine, a bar with needles; cooperative sinkers; a cam shaft with a cam thereon having a section for actuating the needle bar during knitting cycles and an auxiliary section for actuating the needle bar during narrowing cycles; lace mechanism including a dipping frame, and a lace bar with points to transfer fabric loops between adjacent needles; a normally idle cam on the cam shaft for actuating said dipping frame; means for shifting the cam shaft for operation of the last mentioned cam to determine the performance of the machine of narrowing cycles for lace purposes; a measuring chain to control the shifting mechanism; means for partially shifting the cam shaft to enable use, during a part rotation of said shaft, of a portion of the auxiliary section of the knitting cam aforesaid to actuate the needle bar for the purpose of pre-forming a course of new loops over the nibs of the sinkers without incidental casting of the loops of the previous course on said needles, and without initiating a narrowing cycle. 95

6. A point bar for the lace mechanisms of full fashioned stocking knitting machines, having regular points for transferring fabric loops between different needles of the knitting machine; and special shorter points for closing the beards of other needles to effect, concurrently, release of loops on such needles. 100

7. A point bar for lace attachments of full fashioned stocking knitting machines, having alternate regular points for transferring fabric loops between different needles of the machine; and intermediate special short points for closing the beards of other needles to effect release, concurrently, of previously formed loops on such needles. 110

8. The method of producing anti-ravel fabric on a flat knitting machine fitted with a lace bar, which comprises pre-forming a course of loops over the sinker nibs without casting them; then raising the needles with the pre-formed loops in the needle hooks; then bringing the points of the lace bar into action and causing the needles and the points to descend together with incident drawing of the pre-formed loops through loops of a previous course on the needles and engaging of the old loops on alternate needles by the lace points; then alternately shifting the lace bar and causing the latter to transfer the old loops engaged by them to adjacent needles; then actuating the needles to draw a new course of loops from fresh yarn; and continually repeating the described cycle. 120

9. The method of forming anti-ravel fabric in accordance with claim 8, and shifting the lace bar alternately in opposite directions during successive cycles. 130
